J. J. LARSON,
WIRE STRETCHER,
APPLICATION FILED JUNE 19, 1917.

Patented Jan. 22, 1918.

UNITED STATES PATENT OFFICE.

JULIUS J. LARSON, OF DURAND, WISCONSIN.

WIRE-STRETCHER.

1,254,415.

Specification of Letters Patent. Patented Jan. 22, 1918.

Application filed June 19, 1917. Serial No. 175,690.

To all whom it may concern:

Be it known that I, JULIUS J. LARSON, a citizen of the United States, residing at Durand, in the county of Pepin and State of Wisconsin, have invented certain new and useful Improvements in Wire-Stretchers, of which the following is a specification.

My invention relates to wire stretchers, and comprehends improvements to that class 10 commonly known as "step-by-step type".

The principal object of the present invention is to provide a wire stretcher which is adapted to be mounted upon a fence post and stretch the wire strand past the same 15 and retain it into engagement with the post, thus facilitating the stapling or otherwise securing the wire strand to the post.

Another important object of the invention is to provide a wire stretcher of this type 20 which is effectively retained against tilting or turning on the fence post and thereby cause the pull to be in a direct line with the wire strand, and not at an angle thereto as is the case with some types of wire 25 stretchers.

A further object resides in the provision of a wire stretcher, the frame of which is formed from a single length of rod which is formed so as to rigidly brace that part 30 of the frame which is adapted to engage the post.

Still another object of the invention resides in the provision of a wire stretcher which has a guide associated therewith, 35 which will facilitate the engagement of the wire strand therein and effectively guide the same.

Another general object resides in the provision of a wire stretcher which is compact 40 and which consists of few parts, which are not likely to become inoperative, which may be quickly and readily attached and detached with and from the fence post, and which may be manufactured and placed on the 45 market at a minimum cost.

The above objects together with others will be fully apparent upon reference to the following detailed description and accompany drawing.

50 The invention consists of constructions, combinations, arrangements and operations which will be hereinafter specifically set forth and the inventive features will be fully recited in the appended claims.

On the drawing:

55 Figure 1 is a top elevation of my improved wire stretcher in operative position, the fence posts being shown in section,

Fig. 2 is a side elevation of the same taken at right-angles to Fig. 1, and

60 Fig. 3 is a fragmentary view taken on line 3—3 of Fig. 1 and looking toward the operating lever.

Referring in detail to the drawing, wherein like characters of reference designate like 65 parts in all the views, the numeral 5 designates a length of rod which possesses the necessary rigidity. This length of rod 5 is extended to provide a side bar 6 which is bowed intermediate its ends to provide a 70 member 7, which is adapted to accommodate the fence post.

This length 5 is bent at right-angles as at 8 and 9 and extended reversely and in 75 parallelism with the side bar 6. This reversely extended portion is substantially rectangular in cross section and is formed with rack teeth at its opposite side edges. This part having the rack teeth thereon shall be hereinafter referred to as a rack bar 80 10. From the forward end of the rack bar the length of rod is curved longitudinally and lies against the member 7 as indicated by the numeral 11. This lends rigidity to the device. From the longitudinally curved portion 11, the rod is extended inwardly and obliquely with respect to the longitudinal axis of the rack bar and is integrally connected with the forward end of the side bar 85 6 as at 12.

90 The extremity of that part of the rod 5 which constitutes the side bar 6 is formed with horizontally disposed convolution 13 which terminates into an upwardly and angularly disposed guide lug 14. This guide 95 lug is adapted to overlie the wire strand and retain the same in a position where it will move over the convolution 13.

Longitudinally movable over the rack bar 10 is an operating lever 15 which carries 100 pivoted pawls 16. Also pivotally mounted on the lever 15 and between the pawls 16 are wire clamping elements 17. These clamping elements 17 are disposed in alignment with the guide lug 14 and both this 105 lug and the wire clamping element are disposed so that the wire strand will bear against the fence post as clearly illustrated

in Fig. 1. Thus it will be seen that the lever 15 may be locked into position on the rack bar 10 and that the operator will have the use of both hands in stapling the wire strand 5 to the post.

A resilient post engaging band 18 is accommodated in the bowed member 7 and has one end attached to this member adjacent one end of the same. This post engaging member 18 is adapted to extend around the post as illustrated in the drawing and is formed with one end of a chain or other flexible element 20. In order to retain the resilient band 18 into binding engagement 15 with the post a hook 21 is mounted in the rod 5 adjacent to that end of the band which is immovable and is adapted for engagement with the flexible element 20.

In order to prevent the device from slipping around the fence post, a claw 21 having teeth at its opposite end which are adapted to be embedded in the post as shown in the drawing is provided and is pivotally connected with the band 18 as at 22. This claw 25 is of a shape to conform to the contour of the fence post.

From this disclosure the operation of the device will be readily apparent and I wish to here state that the form of the invention 30 illustrated in the accompanying drawing is merely illustrative and that I may make such legitimate changes and modifications that may be embodied in the herewith appended claims.

35 What is claimed is:—

1. A wire stretcher, comprising side bars connected together at their respective ends to form a frame, one of said side bars being bowed inwardly for a portion of its length 40 to provide a post receiving space, means for fastening the frame to the post, a lever arranged to travel along one of said side bars, and wire clamping members carried by said lever.

45 2. A wire stretcher, comprising a pair of side bars connected together at their respective ends to form a frame, one end of said frame being extended and convoluted to form a guide loop offset from the longitudinal center of the frame 50 and alined with said inwardly bowed portion, teeth formed on the bar opposite the post engaging bar and alined with said inwardly bowed portion and the loop, and a wire stretching lever movable along said toothed portion and carrying actuating pawls engageable with said teeth.

said last mentioned bar, a lever arranged to slide along said toothed portion, pawls carried by said lever and engageable with said teeth and a plurality of cam faced fastening members pivoted to one side of said lever and arranged to clamp the wire therebetween. 55

3. A wire stretcher including spaced side bars connected together at their respective 60 ends to form a frame, one of said side bars having an intermediate portion thereof bowed inwardly to provide a post receiving space, a post engaging strip secured to said inwardly bowed portion, and a chain carried 65 by said strip, said chain adapted to be passed around the post and secured to the frame, a wire stretching means supported on said frame.

4. A wire stretcher, including a frame, 70 comprising side bars, one of said side bars having an intermediate bowed portion to receive a supporting post, a post engaging strip secured to said bowed portion, a post engaging claw carried by said strip and 75 adapted to be embedded in the post, a chain carried by one end of said strip, a hook positioned on the frame to receive the free end of the hook, and wire stretching means supported by said frame. 80

5. A wire stretcher, including a pair of spaced side bars secured together at their respective ends to form a frame, one of said side bars being bowed inwardly for a portion of its length 85 to provide a post receiving space, one end of the frame being extended and convoluted to form a guide loop offset from the longitudinal center of the frame and alined with said inwardly bowed portion, teeth formed on the bar opposite the post engaging bar and alined with said inwardly bowed portion and the loop, and a wire stretching lever movable along said toothed portion and carrying actuating pawls engageable with said teeth. 95

In testimony whereof I affix my signature in presence of two witnesses.

JULIUS J. LARSON.
